GANTRY CAR ICER

Arba J. Matthews, Watsonville, Calif., assignor to The Union Ice Company, a corporation

Application December 1, 1953, Serial No. 395,428

2 Claims. (Cl. 198—188)

My invention relates to means for use in the process of supplying blocks of ice to the ice bunker openings at the top of refrigerator cars and is especially concerned with a mechanism for supplying very large quantities of ice to entire train loads of refrigerator cars in a short space of time.

In the movement of produce requiring refrigeration; for example, lettuce, the growing season and the growing rate are such that entire train loads of refrigerator cars loaded with lettuce must be supplied in the shortest possible space of time with ice for cooling the produce in transit. Usually, the ice is manufactured in 300 pound blocks and is stored for a short time until a train arrives for icing. Then the ice blocks are carried to the refrigerator cars, are broken up into smaller, irregular chunks, and are introduced through the bunker openings or hatches in the top of the individual cars to remain in ice bunkers at the opposite ends of the cars during transit. The ice blocks are sometimes broken up into fine shavings or small chips or virtually snow before loading into the refrigerator cars, but in the present instance the generally rectangular blocks are usually broken down into pieces not much smaller than 10 or 20 pounds each.

It is therefore an object of my invention to provide a means for quickly supplying refrigerator cars with ice of the character indicated.

Another object of my invention is to provide a car icer effective for icing one or several entire trains of refrigerator cars in a very short space of time.

Another object of my invention is to provide a means for icing refrigerator cars in whatever location the cars happen to be on the track.

Another object of my invention is to provide a car icer effective with very little manual labor to serve in the icing of a large number of refrigerator cars.

Another object of my invention is to provide a mechanism which is relatively simple and inexpensive for handling a large volume of ice in a short space of time at a number of different icing locations.

A still further object of my invention is to provide a car icing device which utilizes many standard principles of ice handling, yet is effective to permit the rapid icing of train loads of refrigerator cars.

A still further object of my invention is to provide a car icer which is relatively safe in its operation.

Other objects, together with the foregoing, are attained in the embodiment of the gantry car icer of my invention described in the accompanying description and illustrated in the accompanying drawings, in which:

Figure 1 is a plan of a gantry car icer constructed in accordance with my invention shown in the operation of icing a refrigerator car, portions of the structures being broken away to reduce the size of the figure and part of the superstructure of the gantry car icer being removed on a horizontal section plane in order to disclose the interior structure.

Figure 2 is an enlarged view showing the gantry car

2

icer in icing position, certain portions being broken away to reduce the size of the figure.

Figure 3 is a cross section, the plane of which is indicated by the line 3—3 of Figure 2.

5 Figure 4 is an end view of the gantry car icer of my invention, portions of the associated trestle structure being shown in cross section.

Figure 5 is an enlarged detail of part of the platform mechanism utilized in the gantry.

10 Figure 6 is a side elevation, portions being broken away to reduce the size of the figure, of the platform controlling structure shown in Figure 5.

Figure 7 is a detail in cross section, the plane of which is indicated by the line 7—7 of Figure 2.

Figure 8 is a detailed cross section, the section line being indicated by the line 8—8 in Figure 2.

Figure 9 is a detail showing in side elevation the propulsion structure or driving mechanism for the gantry.

15 Figure 10 is a cross section, the plane of which is indicated by the line 10—10 of Figure 9.

20 While the construction of the gantry car icer of my invention can be varied considerably, depending upon the particular environment in which it is to be utilized and depending also upon the particular duty that it is to perform, it has very successfully been incorporated and operated in the form shown herein. The gantry car icer is located preferably between one car track 6 and a parallel car track 7 on each of which refrigerator cars, such as 8 and 9, are drawn in train in the customary fashion. A typical refrigerator car 8 is provided in its roof on opposite sides of the center and near the opposite ends with one or more hatches 11 or bunker openings, through which ice can be introduced into the interior of the car.

25 30 35 Preferably disposed midway between the tracks 6 and 7 so that cars in train on both of them can be simultaneously loaded, is a trestle frame 12, preferably fabricated of suitable material such as lumber. The trestle extends between the tracks 6 and 7 and parallel thereto for at least the length of the longest trains stationed on the tracks 6 and 7. The trestle also extends to a supply house (not shown) wherein ice blocks of a suitable nature are provided. Preferably, the height of the trestle frame 12 is about equal to that or is a little more than that of the roof 13 of the adjacent refrigerator cars on the tracks 6 and 7.

40 45 50 55 The trestle frame 12 at its upper end carries an ice way 13 conveniently in the shape of a trough having a bottom 14 and opposite confining sides 15 and 16. Preferably the trough is lined with a suitable material, such as metal, to support and guide blocks 17 of ice resting therein. The ice way 13 is substantially level or follows the contour of the car tracks 6 and 7, although at one end adjacent the ice supply house it may descend on an incline in a well known way to receive individual ice blocks.

60 65 70 Adapted to straddle the trestle frame 12 is an icing gantry, generally designated 21, which includes a framework 22 mounted on wheels 23 resting on rails 24 and 26 spaced apart somewhat more than normal gauge. The rails 24 and 26 extend alongside the trestle 12 and follow generally the elevation and contour of the car tracks 6 and 7. They are of substantially the same total length as that of the trestle 12. The gantry frame 22 is propelled on the rails 24 and 26 in its position straddling the trestle 12 by means of an electric driving motor 27 (Figure 9). The motor is supplied with electric current from conductors 28 and 29 on the trestle frame 12. Appropriate shoes or trolley collectors are included in conductors 31 and 32 which extend to a control panel 33 mounted on the gantry frame 22 and from the controller

go to the motor 27. The motor acts through a suitable

reduction gear 36 to drive a chain 37 connected to a sprocket 38 joined to one of the wheels 23. Preferably, the drive structure, as shown in Figure 9, is duplicated for at least two of the wheels 23 supporting the gantry so that adequate and even driving power is furnished to move the gantry up and down the rails 24 and 26 alongside the tracks 6 and 7. The control panel 33 is provided with controllers so that the gantry 21 can be stopped in any desired location alongside the tracks 6 and 7.

Protected by a roof 38 at the upper portion of the gantry frame 22 is an operator's platform 39 at an elevation substantially that of the ice way 13 at the top of the trestle 12. The platform 39 is actually in two parts located either side of the trestle and extends to within a short distance of the sides of the ice way. The framing of the gantry is such that it clears the trestle 12 in all respects except for the contact of the electrical accumulators with the conductors 28 and 29. With this arrangement, therefore, an operator standing on the platform 39 near the control panel 33 can run the icing gantry up and down the rails 24 and 26 always in close operating relationship with the ice way 13.

In order that ice blocks can be handled on the gantry, the platform 39 is in part covered and bridged across by a metallic plate 41 constituting an ice slide disposed not only over the platform portions 39 but also disposed over or lying above the ice way 13. A part of the ice slide extends laterally to the two side extremities of the platform 39 whereas the central portion of the plate forming the ice slide 41 exactly overlies the ice way 13, particularly the bottom 14 thereof. In addition, the plate 41 is extended or is provided with means for diverting ice from the bottom 14 of the ice way 13 to the ice slide 41. This means includes a downwardly directed metallic flap 42 or ramp at one end of the ice slide plate 41. The terminus of the ramp or flap 42 is in contact with or substantially in contact with the lining in the bottom of the ice way 13. Also, the ice slide 41 is for a portion of its length provided with side walls 43 and 44 (Figure 2) approximately overlying the side walls 15 and 16 of the ice way trough and further having inclined ends 46 and 47 to serve as guides for ice blocks.

In order to convey or propel ice blocks from the position of storage into a position for use anywhere along the tracks 6 and 7 at an elevation approximately equal to that of the top of the cars, the ice way 13 in its bottom is provided with a channel 51 in which the upper run 52 of a conveyor chain is disposed. The conveyor chain not only operates in the channel 51 in the ice way but likewise lifts slightly near the ramp 42 to run in a second channel 53 formed in the bottom of the ice slide plate 41. The upper chain run 52 then returns to the channel 52 in another portion of the trestle ice way.

The chain 52 at its opposite ends is trained about appropriate sprockets 54, one of which is shown in Figure 4, and the lower run 56 of the chain returns in a guide trough 57 included in the framework 12 of the trestle. An appropriate drive mechanism (not shown) revolves the shaft 58 on which the sprocket 54 is mounted so that the chain 52 is advanced in the direction of the arrow 59, usually in a continuous fashion. The chain at appropriate intervals in its length is provided with upstanding enlargements 61 (Figure 7) effective to engage behind one end of a cake or block of ice. Often ice blocks of the 300 pound size are conveyed with a narrow face on the bottom, but in the present instance they are preferably propelled by the chain and enlargements 61 in the direction of their length with a wide face on the bottom.

By the operation of this chain conveyor structure, ice blocks 17 in the ice way 13 are advanced along the top of the trestle until they come to the gantry. There they are lifted and advanced by the chain rising over the ramp 42 onto the ice slide 41. This occurs whether or not the gantry happens to be stationary in one position

or happens to be travelling to or fro on the rails 24 and 26. Usually, the gantry makes periodic stops or reduces its speed substantially near the bunker or hatch openings 11 of the respective cars but if desired the gantry can operate continuously. In the event the gantry is moving toward the source of supply of the ice blocks, the speed of operation of the conveyor chain can be slowed so that the relative speed of receiving ice blocks on the gantry frame is at a desired rate while if the gantry happens to be moving away from the source of supply of ice blocks the speed of the chain 52 can be increased to maintain the desired rate of receipt of ice blocks at the gantry.

Ice blocks received on the gantry on the ice slide 41 and disposed between the guides 43 and 44 are preferably deflected laterally for further handling. Since the ice slide 41 itself is a plate which extends to the opposite side of the gantry frame on the platform 39, I provide a means for appropriately deflecting the ice blocks either way. Disposed above the plate 41 are curved barriers 66 and 67 which extend from points near the chain to the edges of the platform 37.

At the ends of the barriers 66 and 67 are disposed circular sockets 68 and 69 while similar circular sockets 71 and 72 are provided at the ends of the walls 43 and 44. A section of curved channel 73 is provided of a sufficient length slightly to overlap the wall 43 and the barrier 67, for example, and is provided with downwardly extending pegs 74 and 76 (Figure 8) so that the curved and removable channel 73 can be pegged into the sockets either in the full line position or in the dotted line position shown in Figure 2. The removable channel 73 extends over the chain 52 and does not interfere with the flights or enlargements thereon and furthermore is reinforced and held in position by a support pin 77 adjacent its center portion which rests on the plate 41.

By appropriately positioning the removable channel 73, ice blocks arriving on the ice slide 41 are diverted laterally either to the right or to the left so that the enlargements completely disengage from the ice blocks as the ice blocks turn aside.

In order to conduct the ice blocks from their diverted location toward the bunker openings or hatches 11, I provide on either side of the gantry frame 22 a pair of platform aprons 81 and 82. These aprons are preferably connected to the gantry frame by hinges 83 so that in a lowered position, as shown in the figures, they are at least in part supported by safety chains 84 extending from the outer portions of the aprons to anchors on the gantry frame.

The aprons can be moved from their substantially horizontal positions, in which they are in effect continuations of the platform 39, into an upper position in which the aprons are substantially vertical. In their raised position, they serve as barriers or blocking walls to prevent the accidental discharge of any ice blocks which might be on the ice slide 41 and so especially prevent accidental dislodgement of any ice during movement of the gantry. The aprons 81 and 82 are preferably constructed of metallic frameworks with wooden flooring matching the flooring of the platform 39, and have metallic apron extensions 85 to assist in bridging the distance between the edge of the apron and the opening 11.

When an apron is lowered, as shown in Figure 4, for example, an operator standing thereon with a suitable implement splits and breaks up the ice blocks 17 passing over the apron from the ice slide 41 so that individual pieces or chunks of ice then travel over the apron 86, largely by gravity, into the opening 11. It is not necessary to shave or crush the ice block but a few strokes of the implement are sufficient to shatter the 300 pound block into suitable fragments. While the gantry is in or near the position shown in Figure 1, for example, sufficient ice is diverted to charge or fill the bunker 11. When that has been accomplished, the gantry is moved along or continues to move along slowly to the next opening.

It is possible to move the gantry with the aprons 81 and 82 extended as shown, but it is usually preferred to move the aprons into their retracted or vertical position for greater safety during the movement of the gantry. For that reason there is provided a quick acting mechanism for lifting and lowering the aprons, as shown especially in Figures 5 and 6.

On the gantry frame 22 above each of the aprons 81 and 82 is a suitable electric drive motor 86 which operates through a reduction gear 87 to revolve a shaft 88 carrying a winch drum 89 thereon. The winch drum has oppositely wound on it a pair of cables 91 and 92 trained over pulleys 93 and 94 and also trained over guide pulleys 96 and 97. Furthermore, the cables are led over guide wheels 98 located underneath the apron at the opposite sides thereof and terminate in spring mountings 101 secured to the sides of the apron.

With this arrangement, when the motor is properly energized, the apron is lowered until the chains 84 are taut. When the motor 86 is reversely energized, it winds in the cables 91 and 92 coiling them on the drum 89 and lifting the apron to its uppermost position, at which time an automatic stop (not shown) de-energizes the motor. In the event the automatic stop does not act exactly at the instant that the platform apron is vertical, the spring members 101 yield slightly to avoid damage. In practice, the circuit energizing the motor 86 and its companion motor on the opposite side is preferably interconnected, either with an alarm or with the controller for the motors 27 so that, if desired, the gantry can not be moved until the aprons 81 and 82 are both in their vertical, safety positions. Then, whenever the gantry is stopped, either the apron 81 or the apron 82, or both of them, can be lowered for icing the adjacent car.

With this structure it is possible for a single icing gantry to travel alongside two trains of refrigerator cars, to receive a continuous supply of block ice from an appropriate source, to divert the received block ice at any point along the length of the trains to an exact registry with the bunker openings on the adjacent car or cars, to have the ice readily broken into suitable chunks by an attendant, and then to move along to the next station, no matter where located, without interrupting the supply of ice. All of this is done without any danger particularly if the aprons 81 and 82 are lifted during motion of the gantry. The arrangement is also such that merely by extension of the trestle frame 12 and of the rails 24 and 26 it is possible for the same gantry to service even two trains on the tracks 6 and 7 or to service individual cars in extremely long trains in the event only some of the cars need icing. Since the ice blocks are already

elevated on the trestle, the power that it is necessary to supply the gantry is merely that required to move the gantry itself along the virtually level rails 24 and 26 and to operate the incidental mechanism, such as the aprons 81 and 82. It is therefore not necessary to have heavy electrical conductors 28 and 29 as it would be if ice elevating or crushing mechanism were included in the travelling gantry. By appropriate radio-telephone communication between the operator's station on the platform 39 and the central supply establishment, the rate of advance of the conveyor 52 is appropriately regulated, the ice gantry is dispatched to an appropriate location along the tracks 24 and 26 in the event not all of the train cars have to be iced, and the overall icing of one, two or more trains is conducted with great efficiency and celerity.

What is claimed is:

1. A gantry car icer comprising a trestle including a frame extending to an elevation about equal to the height of said car, an ice way on said frame at said elevation, said ice way including a trough having upstanding sides and a bottom for supporting an ice block, a first depressed channel set into and extending along said bottom, a gantry frame straddling and movable along said trestle, a horizontally extending ice slide plate on said gantry frame overlying said ice way at an elevation just above said sides, walls on said ice slide plate in vertical registry with said sides of said trough, a second depressed channel set into and extending along said ice slide plate in vertical registry with said first channel, means on said gantry frame continuing one of said walls and curving over said second channel, a continuous conveyor chain having one portion disposed in said first channel and another portion disposed in said second channel, and enlargements on said conveyor chain for engaging ice blocks supported on said bottom of said trough and on said ice slide plate.

2. A structure as in claim 1 in which said gantry frame has a flap forming a ramp extending between said trough sides and from said ice slide plate to said trough bottom.
